ABSTRACT OF THE DISCLOSURE

A variable gain amplifier connected in series with a gated monostable multivibrator, wherein the multivibrator will operate to change states only if a gating circuit is properly biased and the output of the amplifier exceeds the trigger level of the multivibrator.

BACKGROUND OF THE INVENTION

In many situations it is desirable to detect a predetermined input dependent upon an external gating function. To accomplish this, it has been the general practice to place an amplifier in series with a monostable multivibrator; shunt the output of the multivibrator with a gating function and connect the combination to an AND gate so that there is an output only when the gating function and the output of the multivibrator coincidentally appear at the input to the AND gate.

A problem with the prior art is that the propagation delay is on the order of 100 nanoseconds. Also, the devices are bulky and weighty.

SUMMARY OF THE INVENTION

In accordance with the present invention an amplifier is placed in series with a monostable multivibrator. The multivibrator will not operate unless enabled by a gating function. Thus, when the gating function is turned off, the output of the multivibrator will be zero. When the gating function is set to enable the multivibrator to operate when triggered by the amplifier, the output of said multivibrator will be a pulse of duration in accordance with the time constant of the multivibrator. Propagation delay of the invention is on the order of 50 nanoseconds.

BRIEF DESCRIPTION OF THE DRAWING

FIG. 1 is a block diagram of the prior art;

FIG. 2 is a block diagram of the invention;

FIG. 3 is a family of curves identifying the waveforms at different nodes of the circuit of FIG. 2; and

FIG. 4 is a schematic diagram of the invention.

DESCRIPTION OF THE PREFERRED EMBODIMENTS

FIG. 1 is a block diagram of the prior apparatus for accomplishing the detection of a predetermined input when said input is dependent upon an external gating function. An amplifier 48 is placed in series with monostable multivibrator 49. The output of multivibrator 49 is shunted with gating function 51 and the combination connected to AND gate 50. There can be an output 52 only when gating function 51 and the output from multivibrator 49 appear coincidentally at the input to AND gate 50.

FIG. 2 is a block diagram of the preferred embodiment of the present invention. A pulse coupled to input 37 is amplified by a variable gain amplifier 35. The output of amplifier 35 is fed into a monostable multivibrator 36. Gating function 38 enables the monostable multivibrator 36 to trigger if the output from amplifier 35 is large enough. If there is no gating voltage 38 the multivibrator will be disabled, thus even a very high amplifier output will not trigger the monostable multivibrator. The circuit

2

is arranged so that when there is no input to monostable multivibrator 36 the introduction or removal of gating voltage 38 will not produce an output at output terminal 39.

5 The operation of the embodiment shown in FIG. 2 may be illustrated by the waveforms of FIG. 3 and the schematic diagram of FIG. 4. During the time interval t_0-t_1 the amplifier 35 is quiescent. The output from amplifier 35, which is represented by voltage V_2 of FIG. 3b is equal to zero, as are the input voltage of FIG. 3a, the gating voltage of FIG. 3c and the output voltage of FIG. 3e. FIG. 10 FIG. 3d illustrates a voltage at some potential V_1 which will disable the monostable multivibrator 36. During the period t_1-t_2 an input pulse causes the output V_2 of the amplifier 35 to rise to potential V_t which is equal to the threshold voltage needed to trigger the monostable multivibrator 36. Since there is no gating voltage 38, transistor Q_5 is turned off and the emitter voltage of transistor Q_3 is held at potential V_1 . Voltage V_1 is frozen so that it is higher than V_t , the threshold voltage needed to trigger monostable multivibrator 36. So long as V_2 does not exceed V_1 , transistor Q_3 cannot cause the cycle of the monostable multivibrator to begin. At time t_3 the gating voltage is raised to V_g . This causes transistor Q_5 to saturate and V_1 drops to zero. When a second pulse of magnitude V_t occurs at time t_4 voltage V_2 is now greater than V_1 and monostable multivibrator 36 will operate through one cycle, turning off at time t_6 . The duration of the pulse at output terminal 39 may be adjusted by changing the time constant of resistor 29 and capacitor 30. Thus there can be output up to time t_6 even through the input voltage ceases at time t_5 .

25 Consider the situation when there is a gating voltage 38, V_1 equals zero, there is no input at input 38 and V_2 also equals zero. In this quiescent condition transistor Q_4 is saturated, output 39 is effectively zero and the base to emitter junction of Q_4 is essentially a short circuit. When gating voltage 38 is removed, potential V_1 changes from zero to some higher potential. If diode D_3 were not in the circuit, transient currents would cause transistor Q_4 to change states creating some regenerative action in the circuit thus affecting output 39. With diode D_3 in the circuit, potential V_3 is greater than V_1 so long as there is gating voltage 38. When gating voltage 38 is removed V_1 rises until diode D_3 becomes back biased. As V_1 rises, potential V_3 does not change thus transistor Q_4 will not shift out of its quiescent state and output 39 will remain essentially zero.

30 By way of illustration only, a gated threshold amplifier as illustrated in FIG. 4 may have the following component values:

$$V_0 = +12 \text{ volts}$$

Resistor 10— 51Ω

Capacitor 11— $15 \mu\text{farad}$

Resistor 12— $10\text{K}\Omega$

Capacitor 13—1 farad

Resistor 14— $10\text{K}\Omega$

Resistor 15— $2\text{K}\Omega$

Resistor 16— 100Ω

Resistor 17— $2\text{K}\Omega$

Capacitor 18— $1 \mu\text{farad}$

Resistor 19— $2\text{K}\Omega$

Variable resistor 20— $2\text{K}\Omega$

Capacitor 21—1 farad

Capacitor 22— $1 \mu\text{farad}$

Resistor 23— $2\text{K}\Omega$

Resistor 24— 200Ω

Coupling capacitor 25— 200 picofarad

Resistor 26— $12\text{K}\Omega$

Resistor 27— $3\text{K}\Omega$

Resistor 28— $2\text{K}\Omega$

Resistor 29— $15\text{K}\Omega$

Capacitor 30—.001 μ farad
 Output resistor 31—5K Ω
 Resistor 32—2K Ω
 Resistor 33—1K Ω
 Resistor 34—5K Ω
 Resistor 42—5K Ω
 Resistor 43—1K Ω
 Resistor 44—2K Ω
 Resistor 45—51 Ω
 Resistor 46—10K
 Transistor Q₁—2N2412
 Transistors Q₂ through Q₅—2N744
 Diodes D₁ through D₃—1N3064

While there have been shown and described and pointed out the fundamental novel features of the invention as applied to a preferred embodiment, it will be understood that various omissions and substitutions and changes in operation may be made by those skilled in the art without departing from the spirit of the invention. It is the intention therefore, to be limited only as indicated by the scope of the following claims.

The invention described herein may be manufactured and used by or for the Government of the United States of America for governmental purposes without the payment of any royalties thereon or therefor.

What is claimed is:

1. An apparatus for detecting a predetermined input level and triggering a monostable multivibrator, the ability to trigger dependent upon whether said monostable multivibrator is enabled or disabled by a gating voltage, said apparatus comprising:

a variable gain amplifier having an output;
 a monostable multivibrator having inputs;
 said monostable multivibrator having a first and a sec-

ond transistor, each having an emitter, a collector, and a base; the output of said variable gain amplifier being coupled to an input of said monostable multivibrator; a gating circuit having an output coupled to another input of said multivibrator; said gating circuit being a switch which grounds the emitter of said first transistor of said multivibrator to enable the apparatus; and said monostable multivibrator being arranged so that said monostable multivibrator will change states when a pulse of a predetermined magnitude is coupled from said amplifier to said monostable multivibrator and said monostable multivibrator is enabled by the presence of an output from said gating circuit.

2. The apparatus of claim 1 wherein:

said gating circuit has a transistor with an emitter, collector, and base; and a diode is connected from the emitter of said second transistor of said multivibrator to the emitter of said first transistor of said multivibrator so that said diode prevents said second transistor from changing states when a disabling voltage is placed on the base of said gating circuit transistor.
